(57) **CLAIM**

The ornamental design for a string light, as shown and described.

DESCRIPTION

FIG. 1 is a front, top perspective view of a string light, showing my new design;

FIG. 2 is a rear, bottom perspective view thereof;

FIG. 3 is a front elevation view thereof;

FIG. 4 is a rear elevation view thereof;

FIG. 5 is an enlarged left side elevation view thereof;

FIG. 6 is an enlarged right side elevation view thereof;

FIG. 7 is a top plan view thereof;

FIG. 8 is a bottom plan view thereof; and,

FIG. 9 is an enlarged view of detail "9" identified in FIG. 1. The evenly spaced broken lines in the figures illustrate portions of the string light that form no part of the claimed design. The dash dot dash lines in FIGS. 1 and 9 are for the purpose of illustrating the enlarged view indicators and form no part of the claimed design.

The string light is shown with a symbolic break in its length. The appearance of any portion of the string light between the break lines, and the break lines themselves, form no part of the claimed design.
